UNITED STATES PATENT OFFICE.

JAMES H. WARD, JR., OF BUCHANAN, MICHIGAN, ASSIGNOR TO JAMES H. WARD & SON, INC., OF BUCHANAN, MICHIGAN, A CORPORATION OF INDIANA.

MAIL BOX.

Application filed July 21, 1927. Serial No. 207,328.

The present invention relates to mail boxes.

More particularly the present invention relates to receptacles suitable for use in 5 apartment buildings or other places where it is desirable to have a battery of receptacles which may be opened simultaneously by a person having the proper key and which permits the selective opening of each of said 10 receptacles by a person having the key to that particular receptacle without permitting access to the others of said receptacles.

The present invention constitutes an improvement over the structure disclosed and 15 claimed in application Serial No. 103,445, filed April 21, 1926, by the present applicant.

An object of the present invention is to provide a closure for a mail box which is sturdy in construction, simple to assemble 20 and which involves a minimum of parts.

A further object is to provide a closure for a mail box made up for the most part of simple stampings, which may be readily assembled and which will present a sturdy construction, but which requires only a minimum of skill in manufacture. 25

Further objects will appear as the description proceeds.

Referring to the drawings—

30 Figure 1 is a view in front elevation of one embodiment of the present invention;

Figure 2 is a horizontal sectional view taken along the plane indicated by the arrows 2—2 of Figure 1;

35 Figure 3 is a vertical sectional view taken along the plane indicated by the arrows 3—3 of Figure 1;

Figure 4 is a view in rear elevation of part 40 of the structure shown in the preceding figures, said view being taken in the direction of the arrow 4 of Figure 3;

Figure 5 is a sectional view taken along the plane indicated by the arrows 5—5 of Figure 4; and

45 Figures 6 and 7 are views in perspective of details of construction.

The numeral 1 indicates a casing which may be made up of sheet metal. According to the illustrated embodiment of the present 50 invention, said casing 1 comprises the sheet metal member 2, which is bent in U-shape to form the back member and the top and bottom members of said casing 1. The two side walls of said casing 1 are provided with 55 sheet metal members 3—3. The members 2

and 3 may be joined and riveted together to provide a casing open on one side. Bounding the casing 1 on its open side is the face plate 4, which may be of brass or other material having a presentable appearance. 60 Said face plate 4 may be riveted or otherwise secured to the casing 1, preferably having a flange 4^A extending into said casing. As will be referred to hereinafter, the rivets for securing the lower portion of the face 65 plate 4 to the bottom wall of the casing 1 will preferably have the added function of providing hinge pins for removably swingingly mounting a closure member. The casing 1 is divided into a plurality of compartments, indicated by the numerals 5—5, the dividing walls between said compartments being preferably sheet metal members 6—6 arranged in parallel relationship with the side walls 3—3 of the casing 1. Said sheet 70 metal members 6—6 may be joined to the casing 1 in any preferred manner, being preferably riveted thereto.

As indicated above the rivets for connecting the face plate 4 to the casing 1 along the 75 bottom wall of said casing 1 at the front thereof preferably serve the added function of providing pivot pins. As clearly shown in Figure 3, the pivot pins 7 serve the double function of securing the face plate 4 to the 80 bottom wall of the casing 1 and forming hinge members for the closure member 8. A number of said pivot pins 7 may be provided along the width of the mail box.

The closure member 8 comprises a plurality of pan-shaped members 9—9, each of which includes the face portion 10 and the flange or wall portions 11—11. Adjacent flange or wall portions 11—11 are placed side by side, said wall portions 11—11 being 90 provided with aligned apertures 12—12 for the reception of the rod 13. Said apertures 12—12 and rod 13 are located at the lower portion of the swinging closure 8. Said flange or wall portions 11—11 are also provided with the aligned apertures 14—14 for the reception of the rod 15 at a region disposed preferably more than half way up the swinging closure 8. Said rods 13 and 15 serve to hold the front faces 10 of the pan-shaped members 9—9 in a single plane. Embracing the two intermediate pairs of flange or wall portions 11—11 are a pair of folded members 16—16 adapted to receive the corresponding wall portions 110

11—11 more or less closely and to hold the pan-shaped members 9—9 against separation. Two outermost flange or wall portions 11—11 of the pan-shaped members 9 in the closure member 8 are provided with the folded members 17—17. Figure 6 illustrates a folded over member 16, and Figure 7 illustrates a folded over member 17. It will be noted that both free edge portions 10 of the folded member 16 are provided with the notches 18 and 19 for the reception of the rods 13 and 15, respectively. Only one free edge portion of each member 17 is provided with the notches 18 and 19 the un- 15 notched free edge portion of each member 17 being adapted to abut the ends of the rods 13 and 15 to hold same against longitudinal movement. Inasmuch as one fold of each folded member 17 is visible from the front 20 of the box, said members 17—17 will preferably have a color harmonizing with the material of the closure member 8 and the face plate member 4. It will be clear that the pan-shaped members 9—9 may be readily 25 assembled upon the rods 13 and 15, and that the folded members 16 and 17 may be disposed upon the portions 11—11 of the pan-shaped members 9—9 to form a rigid structure, the end portions of the rods 13 and 15 30 being anchored within the corresponding apertures 12 or 14 of the outside wall portions 11—11 and being held against longitudinal movement by the outer fold of each of the folded members 17—17.

35 After being assembled, the pan-shaped members and the folded members 16 and 17 may be spotwelded together, as indicated by the numerals 19^B—19^B, this structure having the advantage that assembly is rendered 40 very simple and cheap.

It will be noted from an inspection of Figure 3 that the lower flange wall portions 11 of the pan-shaped members 9 are provided with apertures 19^A adapted to loosely receive the upstanding pins 7—7. The closure member 8 will fit within the outline defined by the innermost portions of the face plate 4. When the closure member 8 is swung outwardly so that the upper extremity thereof is free of the adjacent portion of the face plate 4, the closure member 8 may be readily lifted from the pins 7—7 and separated from the casing 1. It will be clear that by swinging the closure member outwardly from its 45 closed position, access will be had to the several compartments 5—5. In order to provide chutes down which the postman may drop mail matter to be deposited in the several compartments chute walls 20—20 are 50 provided which lie in parallel relationship with the walls 6—6—3—3 of said compartments 5. The means providing the chute walls 20—20 do not form any part of the 55 present invention. It will be noted from an inspection of Figure 2 that each sheet metal

member 6 has a chute wall 20 mounted adjacent thereto. Each side wall 3 of the casing 1 also has a chute wall 20 mounted adjacent thereto. The number of chute walls 20 is therefore one more than the 70 number of compartments 5—5. Said chute walls 20—20 are pivotally connected to the adjacent partition walls 6 or end walls 3 by means of rivets 21, the axes of said rivets lying in substantial alignment. Each of the partition walls 6 is provided with an arcuate slot 22 having its axis coincident with the axis of the rivets 21. Said arcuate slots 22 are adapted to receive pins 23 securely mounted in the adjacent chute walls. Said pins 23—23 are provided with heads 24 which maintain said pins 23 in operative relationship with the corresponding partition walls 6 or end walls 3 without danger of interfering with mail matter deposited within the mail box. The front portions of the chute walls 20—20 are secured to the rod 25, which constrains said chute walls to move as a unit about the axis of the rivets 21.

The swinging closure member 8 is provided on its rear side with one or more hook members 26 adapted to hook over the rod 25. Swinging movement outwardly of the closure member 8 will, by reason of the engagement between the hook member 16 and the rod 15, cause the chute walls 20—20 to swing outwardly; the outward swinging movement of said closure member 8 and the chute walls 20—20 being limited by the material defining the ends of the arcuate slots 22—22. The weight of the closure member 8 and the proportions of the parts will preferably be chosen such that after the closure member 8 has been swung outwardly to a convenient angle the weight of said members will tend to hold same in open position. Under these conditions, the back wall of the casing 1, the front closure 8, the chute walls 20 and the stationary walls 6 or 3 provide flaring compartments, simplifying the job of the postman in depositing the mail. After the postman has deposited his mail, he will move the closure member 8 to closed position with a slight push. Engagement of the closure member 8 with the adjacent edge portions of the chute walls 20—20 will, of course, move said chute walls inwardly of the box toward the rear wall of the casing 1.

The numeral 27 indicates a lock which controls the opening and the locking of the closure member 8. Said lock 27 may be of a snap variety, whereby the postman may lock the closure member 8 merely by pushing same to closed position. Access to the various compartments is provided through the individual doors 28—28, which are swingingly supported by means of the rod 15. Said doors swing outwardly of the mail box for permitting access to the interior of the

corresponding compartment 5. Each door 28 swings outwardly of the mail box for permitting access to the interior of the corresponding compartment 5. Each door 28 will be controlled by its individual lock 30, the different locks 30 being responsive to different types of keys, the key to each door being adapted to open only its own door and not any of the other doors. As shown in Figure 3, each of the doors 28 is provided with a backing plate 31, which may be of steel or other strengthening material. Said backing plate is provided with the groove 32 near its upper extremity, providing, with the front face of the door 28, a housing or bearing for the rod 15. Said backing plate 31 is provided with the cut out portion 33 coinciding with peep apertures 34 in the front face of the door 28, whereby to afford a view of the interior of each compartment without requiring the opening of the corresponding door 28.

The lower rod 13, in addition to holding the pan-shaped members 9—9 in proper relationship with one another, has the further function of providing a backstop for each of the doors 28. It will be noted that the lower extremity of each door 28, when said door is in closed position, engages the rod 13, whereby to define the closed position of said door. It will be noted also that the bolt 35 of each of the individual locks 30 is adapted to engage the rear side of the rod 13, whereby said rod 13 provides a striking plate for the bolt 35 of each individual lock 30. As shown in Figure 3, the backing plate 31 is swedged rearwardly, as indicated by the numeral 36, to a sufficient extent to properly position a lock 30 of commercial manufacture, so that the bolt 35 thereof has the proper relationship with the rod 13.

The rear wall of the casing 1 may be provided with openings 37 through which screws may be inserted for securing the mail box to the wall of the building or other supporting member. It will be clear that the supporting screws are protected from tampering under normal conditions by the closure member 8. When said closure member 8 is removed from the casing 1, it is a simple matter to manipulate the screws in the apertures 21, so that the matter of mounting the mail box or dismounting same is a very simple one.

The top flange or wall 11 of each pan-shaped member 9 provides a convenient place for marking the number of the lock 30 of the corresponding door 28. In the event that a tenant had lost the key of his lock, the postman by consulting the number at the top flange or wall 11, could give the tenant the information necessary to secure a duplicate key.

Though a preferred embodiment of the

present invention has been described in detail, many modifications will occur to those skilled in the art. It is intended to cover all such modifications that fall within the scope of the appended claims.

What is claimed is—

1. A closure comprising a plurality of elongated members having their side edge portions provided with flanges, said flanges being provided with two sets of aligned apertures, rods extending through said sets of apertures to hold said members in one plane, and gripping members engaging adjacent flanges of neighboring members to hold said members against displacement in said plane. 70

2. A closure comprising a plurality of elongated members having their side edge portions provided with flanges, said flanges being provided with two sets of aligned apertures, rods extending through said sets of apertures to hold said members in one plane, and gripping members engaging adjacent flanges of neighboring members to hold said members against displacement in said plane, the outside flanges of the two outermost members having end thrust relationship with said rods. 85

3. A closure comprising a plurality of elongated members having their side edge portions provided with flanges, said flanges being provided with two sets of aligned apertures, rods extending through said sets of apertures to hold said members in one plane, and gripping members engaging adjacent flanges of neighboring members to hold said members against displacement in said plane, said gripping members comprising folded over members extending along a substantial length of their corresponding flanges and having notches for receiving said rods and for locating said gripping members. 95

4. A closure comprising a plurality of elongated members having their side edge portions provided with flanges, said flanges being provided with two sets of aligned apertures, rods extending through said sets of apertures to hold said members in one plane, and gripping members engaging adjacent flanges of neighboring members to hold said members against displacement in said plane, the outside flanges of the two outermost members having end thrust relationship with said rods, said gripping members comprising folded over members extending along a substantial length of their corresponding flanges and having notches for receiving said rods and for locating said gripping members. 110

5. A closure comprising a plurality of members placed side by side in a single plane, said members having flanges upon their four sides, parallel flanges being provided with two sets of aligned apertures, rods in said apertures to hold said members 125

in one plane, and gripping members cooperating with adjacent flanges of neighboring members to hold said members in said plane, the other flanges of said members being provided with apertures for the reception of hinge pins to permit the swinging of said closure.

6. A closure comprising a plurality of members placed side by side in a single plane, said members having flanges upon their four sides, parallel flanges being provided with two sets of aligned apertures, rods in said apertures to hold said members in one plane, and gripping members cooperating with adjacent flanges of neighboring members to hold said members in said plane, the other flanges of said members being provided with apertures for the reception of hinge pins to permit the swinging of said closure, the outside flanges of the two outermost members having end thrust relationship with said rods.

7. A closure comprising a plurality of members placed side by side in a single plane, said members having flanges upon their four sides, parallel flanges being provided with two sets of aligned apertures, rods in said apertures to hold said members in one plane, and gripping members cooperating with adjacent flanges of neighboring members to hold said members in said plane, the other flanges of said members being provided with apertures for the reception of hinge pins to permit the swinging of said closure, said gripping members comprising folded over members extending along a substantial length of their corresponding flanges and having notches for receiving said rods and for locating said gripping members.

40 8. A closure comprising a plurality of members placed side by side in a single plane, said members having flanges upon their four sides, parallel flanges being provided with two sets of aligned apertures, rods in said apertures to hold said members in one plane, and gripping members cooperating with adjacent flanges of neighboring members to hold said members in said plane, the other flanges of said members being provided with apertures for the reception of

hinge pins to permit the swinging of said closure, the outside flanges of the two outermost members having end thrust relationship with said rods, said gripping members comprising folded over members extending along a substantial length of their corresponding flanges and having notches for receiving said rods and for locating said gripping members.

9. A closure comprising a plurality of elongated members having their side edge portions provided with flanges, said flanges being provided with two sets of aligned apertures, rods extending through said sets of apertures to hold said members in one plane, and gripping members engaging adjacent flanges of neighboring members to hold said members against displacement in said plane, each of said members being provided with a single door having a locking bolt, one of said rods being disposed adjacent to a swinging extremity of each of said doors to provide a door stop therefor, said locking bolt being positioned to cooperate with said one rod as a lock strike.

10. A closure comprising a plurality of elongated members having their side edge portions provided with flanges, said flanges being provided with two sets of aligned apertures, rods extending through said sets of apertures to hold said members in one plane, and gripping members engaging adjacent flanges of neighboring members to hold said members against displacement in said plane, each of said doors being provided with a backing plate, each of said backing plates having a grooved portion cooperating with said door and one of said rods to form a hinge, each of said doors having its swinging extremity in cooperative relationship with the other of said rods whereby said other rod forms a stop for said door, each of said doors being provided with a locking bolt adapted to cooperate with said other rod whereby said other rod forms a striking plate for said bolts.

Signed at Buchanan, Michigan, this 16th day of July, 1927.
